UNITED STATES PATENT OFFICE

WILLIAM PETER GLINTENKAMP, OF BELLAIRE, NEW YORK, ASSIGNOR TO MAY MANUFACTURING CO. INC., OF NEW YORK, N. Y.

DESIGN FOR A BRIDGE MEMBER FOR AN OPTICAL MOUNTING

Application filed August 29, 1929. Serial No. 32,615. Term of patent 3½ years.

To all whom it may concern:

Be it known that I, WILLIAM PETER GLINTENKAMP, a citizen of the United States, residing at Bellaire, Long Island, in the county of Queens and State of New York, have invented a new, original, and ornamental Design for a Bridge Member for an Optical Mounting, of which the following is a specification, reference being had to the accompanying drawing, forming a part thereof.

Figure 1 is a perspective view of a bridge

member for an optical mounting showing my new design.

Fig. 2 is a top plan view of the same. The dotted lines merely show the relation of the nose bridge member when in use.

I claim:

The ornamental design for a bridge member for an optical mounting, as shown and described.

In testimony whereof I affix my signature.

WILLIAM PETER GLINTENKAMP.
